UNITED STATES PATENT OFFICE

JOHN D. SPALDING, OF CRAFTON, PENNSYLVANIA, ASSIGNOR TO THE NATIONAL SUPPLY COMPANY OF DELAWARE, OF NEW YORK, N. Y., A CORPORATION OF DELAWARE

ROTARY DRAWWORKS BACK BRAKE ASSEMBLY

Application filed June 3, 1929. Serial No. 367,981.

This invention relates to rotary drawworks and more particularly to an assembly for forming a unitary structure drawworks whereby the brake actuating means for the drawworks is supported at the rear of the drawworks and as a unitary part of the drawworks.

The drawworks as no commonly constructed for use in connection with rotary machines for carrying out the rotary process of drilling wells it is customary to provide a hoisting drum having spaced brake bands and a brake actuating means including a brake equalizer which must be assembled on the floor of the drilling rig and lined up with the brake bands of the hoisting drum and secured in position. When thus secured in position the brake actuating means, equalizer and supporting structure is in front of the drum between the drawworks and the rotary machine.

It is an object of this invention to provide a means forming a rigid frame of the posts of a rotary drawworks as commonly constructed so that the rotary drawworks may be installed in position upon the sills of a derrick, and which unitary structure includes a means for supporting the brake actuating means for the rotary drawworks to the rear of the hoisting drum.

Another object of this invention is to provide a rotary drawworks including a plurality of spaced posts between which a rotary drawworks hoisting drum is supported on a shaft, an angle iron secured to the ends of the spaced posts for securing the posts together at their lower ends, and a brake actuating means secured to the angle iron in position and as a unitary structure for actuating the spaced apart brake bands of a rotary drawworks drum.

Other objects and advantages of this invention it is believed will be apparent from the following detailed description of a preferred embodiment thereof as illustrated in the accompanying drawings.

In the drawings:

Figure 1 is a fragmental front elevation of a rotary drawworks embodying this invention.

Figure 2 is a sectional edge elevation taken substantially on the line 2—2 of Figure 1.

Figure 3 is a sectional plan view taken substantially on the line 3—3 of Figure 1.

Figure 4 is a sectional end elevation taken substantially on the line 4—4 of Figure 1.

In a drawworks construction it is common practice to provide a frame including two or more spaced posts 1 and 2 upon which the drum shaft 3 is journaled. Mounted on the drum shaft 3 is a hoisting drum 4 having spaced brake rims 5 upon which brake bands 6 are mounted.

In accordance with the preferred embodiment of this invention illustrated in the accompanying drawings, the spaced apart posts 1 and 2 are secured together by means of an angle iron 7 which is secured to the ends of the posts by means of bolts 8 and within cut-out recesses formed at the lower ends of the posts 1 and 2. The angle iron is thus supported in position to rest upon the sill 9 of the derrick in which the rotary drawworks is mounted. The angle iron when thus positioned on the sill 9 is secured in position by the bolts 8 passing through the sill 9 and may also be secured in position by means of additional bolts 10 positioned between the bolts 8 and passing through the vertical web 11 of the angle iron 7.

The angle iron 7 thus forms a means for holding the posts 1 and 2 together at the lower end of the drawworks construction, and likewise forms a supporting means for supporting the drawworks on the sill 9 of the derrick. The angle iron 7 may, if the frame of the drawworks includes three or more posts, be also connected in the same manner to each of the additional posts by bolts similar to the bolts 8.

In order to provide a unitary structure of drawworks which may be mounted within a drilling rig without requiring the positioning and centering of a brake actuating means, I prefer to mount on the angle iron 7 a pair of spaced brackets 12 which may be securely riveted to the angle iron 7 as indicated at 13. The brackets 12 provide a means to which the dead ends 14 of the brake bands 6 may be secured and locked in position, and also

provide a means for supporting the brake actuating shaft 15 to which the live ends 17 of the brake bands 6 are secured, and by means of which the brake bands 6 are loosened or tightened as desired upon the brake rims 5.

The dead ends 14 of the brake bands 6 are secured to the brackets 12 by eye-bolts 18, the eyes of which are secured to the dead ends 14 of the brake bands 6 passing through bores 19 formed through the brackets 12.

The eye-bolts 18 are secured in position by means of nuts 20 screw-threaded in the ends of the eye-bolts 18. A locked jaw 21 is pivotally secured to each bracket 12 by a pin 22 and fits the nut 20, thus holding the nut 20 locked on the eye-bolt 18 after the nut 20 has been tightened up to the desired degree. When it is desired to adjust the dead ends 14 of the brake band 6, the lock jaw 21 may be rotated on its pivot 22 out of locking position. When in locking position the lock jaw 21 is held by gravity in engagement with the nut 20.

25 The actuating shaft 15 for the live end 17 of the brake band 6 is supported by the bearing brackets 12 by passing through bearing bosses 23 formed in the upper ends of the brackets 12 and within which bearing bosses 30 23 the actuating shaft 15 is journaled. The actuating shaft 15 is also supported from the angle iron 7 by a third bracket 24, which is likewise riveted to the angle iron 7 and supports the outer end of the actuating shaft 15 35 beyond the actuating lever 25.

The means herein illustrated for securing the live end 17 to each brake band 6 to the actuating shaft 15 includes arm collars 26 which are secured to the actuating shaft 15 40 on opposite sides of the bearing boss 23 of the bracket 12. The two arm collars 26 have their arms 27 connected by means of a pin 28 which is releasably held in position by means of a cotter pin 29.

45 The ends of the eye-straps 30 of the brake bands 6 are journaled on the pins 28.

Secured to the actuating shaft 15 intermediate one of the brackets 12 and the bracket 24 at the end of the drum 4 is a bracket 50 31 to which the actuating handle 25 is releasably secured by means of bolts 32. Secured to the bracket 31 is an arm 33 which carries an adjustable weight 34 normally tending to rotate the actuating shaft 15 to a 55 position to release the tension of the brake bands 6 on the brake rims 5.

Having fully described my invention, it is to be understood that I do not wish to be limited to the details herein set forth, but 60 my invention is of the full scope of the appended claims.

I claim:

1. In a rotary drawworks, the combination of a frame including spaced posts, an angle iron secured to the lower ends of said posts,

a drum shaft supported by the posts, a drum mounted on the drum shaft, the drum providing spaced brake rims, brake bands mounted on the brake rims, brackets secured to the angle iron in alignment with the brake rims, means for securing the dead ends of the brake bands to said brackets, and a brake band actuating shaft rotatably supported by the said brackets and secured to the live ends of said brake bands. 70 75

2. In a rotary drawworks, the combination of a frame including spaced posts, an angle iron secured to the lower ends of said post in recesses formed in the posts, a drum shaft supported by the posts, a drum mounted on the shaft, the drum providing spaced brake rims, brake bands mounted on the brake rims, brackets secured to the angle irons and in alignment with the brake rims, means for securing the dead ends of the brake bands 85 to said brackets, a brake band actuating shaft rotatably supported by said brackets and secured to the live ends of said brake bands, and means secured to said shaft for actuating the same. 90

3. In a rotary drawworks, the combination of a frame including spaced posts, an angle iron secured to the lower end of said posts, a drum shaft supported by the posts, a drum mounted on the drum shaft, the drum providing spaced brake rims, brake bands mounted on the brake rims, brackets secured to the angle iron in alignment with the brake rims, the brake band actuating shaft being rotatably supported by said brackets 100 and providing brake actuating arms, means for securing the live ends of said brake bands to said arms, and means for actuating the said brake band actuating shaft. 105

4. In a rotary drawworks, the combination of a frame including spaced posts, an angle iron secured to the lower ends of said posts to maintain the said posts in spaced relation at their lower ends, a drum shaft supported by the posts, a drum mounted on the drum shaft, the drum providing spaced brake rims, brake bands mounted on the brake rims, brackets secured to the angle iron in alignment with the brake rims, means for adjustably securing the dead ends of the 115 brake bands to said brackets, means for locking the latter said means in adjustment, the brake band actuating shaft being rotatably supported by the brackets, means for securing the live ends of said brake bands to said shaft, and means for actuating the said shaft to tighten said brake rims on said brake bands. 120

5. In a device of the class described, the combination of a frame, a derrick sill, an angle iron mounted at the lower end of said frame and extending longitudinally thereof for supporting said frame upon said derrick sill, a hoisting drum supported by said frame, said supporting drum having brake rims at 125 130

its opposed ends, brake bands mounted on said brake rims, brackets mounted on said angle iron in alignment with said brake rims, a shaft journaled in said brackets, means for securing the live ends of the brake bands to said shaft, means for adjustably securing the dead ends of the brake bands to said brackets, and means for rotating the said shaft to actuate the live ends of the brake bands.

6. In combination with a drawworks drum having a pair of brake rims at its opposed ends, of a brake band mounted upon each rim, a supporting angle iron mounted in position to the rear of the axis of said drum, a pair of spaced brackets secured to said angle iron in alignment with said brake rims, a brake actuating shaft journaled in said brackets, means secured to said shaft and to the live ends of the brake bands for actuating the brake bands, the latter said means being aligned with the brake bands and said brackets so that the braking force is transmitted directly to said angle iron, adjusting means for the dead ends of said brake bands, said adjusting means being operatively coupled to said brackets, and means for locking said adjusting means in adjusted position.

7. In a device of the class described, the combination of a frame, a derrick sill, a member mounted at the lower end of said frame and extending longitudinally thereof for supporting said frame upon said derrick sill, a hoisting drum supported by said frame, said supporting drum having brake rims at its opposed ends, brake bands mounted on said brake rims, securing means mounted on said member in alignment with said brake rims, a shaft journaled in said securing means, means for securing the live ends of the brake bands to said shaft, means for adjustably securing the dead ends of the brake bands to said longitudinal member, and means for rotating the said shaft to actuate the live ends of the brake bands.

8. In a drilling rig including a sill, the combination of a drawworks including a frame having spaced posts, an angle iron secured to the lower ends of said posts, said angle iron being adapted to fit upon the sill, a drum shaft supported by the posts, a drum mounted on the drum shaft, the drum providing spaced brake rims, brake bands mounted on the brake rims, brackets secured to the said angle iron, a shaft rotatably supported by said brackets, means for securing the live ends of said brake bands to said shaft, and means for actuating the shaft to tighten the brake bands on said brake rims.

9. In a drilling rig including a sill, the combination of a frame including spaced posts having recesses at the lower ends thereof, an angle iron secured to the lower ends of said posts in the recesses formed at the

ends of said posts to hold the lower ends of said posts in spaced relation, the said angle iron being adapted to fit upon and be secured to the sill, means adapted to secure the angle iron to said sill, a drum shaft supported by the posts, a drum mounted on the drum shaft, the drum being provided with spaced brake rims, brake bands mounted on the brake rims, brackets secured to the angle iron in alignment with the brake rims, means for adjustably securing the dead ends of the brake bands to said brackets, locking means pivotally supported by said brackets for locking the latter said means in adjustment, a brake band actuating shaft rotatably supported by said brackets, crank means for securing the live ends of the brake bands to said shaft, and means for actuating said shaft.

10. In combination with a rotary draw-works supported on a derrick sill including a frame having spaced bearing supports, an angle iron secured to the lower ends of said supports, said angle iron being adapted to fit upon the derrick sill, a drum shaft rotatably journaled in the supports, a drum mounted on the drum shaft, the drum providing a brake rim, a brake band on said brake rim, a bracket secured to the said angle iron, a shaft rotatably supported by said bracket, means for securing the live end of said brake band to said shaft, and means for actuating the shaft to tighten the brake band on said brake rim.

11. In combination with a well hoisting apparatus supported on a derrick sill, the combination of a frame including spaced posts having recesses at the lower ends thereof, an angle iron secured to the lower end of said posts in the recesses formed at the ends of said posts to hold the lower ends of said posts in spaced relation, the said angle iron being adapted to fit upon and be secured to the derrick sill, means adapted to secure the angle iron to said sill, a drum shaft supported by the posts, a drum mounted on the drum shaft, the drum being provided with a brake rim, a brake band mounted on the brake rim, a bracket secured to the angle iron in alignment with the brake rim, means for adjustably securing the dead end of the brake band to said bracket, locking means pivotally supported by said bracket for locking the latter said means in adjustment, a brake band actuating shaft rotatably supported by said bracket, crank means for securing the live end of the brake band to said shaft, and means for actuating said shaft.

Signed at Carnegie, Penna., this 23rd day of May, 1929.
